(57) **CLAIM**

The ornamental design for an securing device for a stand, as shown and described.

DESCRIPTION

FIG. 1 is a perspective view of an securing device for a stand showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front view of the securing device for a stand folded around;

FIG. 9 a perspective view of the securing device for a stand at a first position on the island;

FIG. 10 is a perspective view of the securing device for a stand at a second position on the island; and,

FIG. 11 is a perspective view of the securing device for a stand at a third position on the island.

The broken lines in the drawings illustrate environmental structure and form no part of the claimed design.
